BRASSIÈRE

Jack Wolf, Baltimore, Md.

Application January 13, 1947 Serial No. 721,790

5 Claims. (Cl. 2—42)

1

The subject matter of this invention is concerned with brassières and more particularly is directed to the breast sustaining pockets thereof of the type having a plurality of sections appropriately assembled and secured together to provide youthful and uplift effects for enhancing charm and attractiveness to the wearer. One important object of the invention is realized in the provision of a serviceable and improved brassière having novel pockets each comprising a medially disposed substantially hour glass shaped section or intervenor means having secured thereto laterally spaced segmental wings to characterize substantially cone shaped pockets in which the apex portions thereof are free of the merger of irritating and impinging inside flanges of the spaced wings and the intervenor means. Another object resides in the provision of a brassière of the type alluded to wherein the wings and intervenor means are strengthened by spaced parallel lines of stitching arranged lengthwise of the intervenor means or intermediate panel and widthwise of the wings or sections to characterize in part substantially nested angles diverging outwardly from associated lines of securing means interconnecting the intervenor means and wings and towards the outer margins of both the intervenor means and wings, providing a pattern rendering the effect of causing relatively heavy busts to appear smaller. The invention has a further object to interconnect the spaced vertical concaved margins of the intervenor means with the convex margins of the wings by continuous lines of latticing or fagotting stitching. Other objects and advantages of the invention will appear from the following detailed specification taken with the accompanying drawings wherein:

Fig. 1 is a perspective view of the brassière according to my invention.

Fig. 2 is an exploded view of a breast pocket illustrating the intervenor means or intermediate panel detached from the wings thereof.

Fig. 3 is an enlarged fragmentary and inside view of one of the breast pockets, and

Fig. 4 is an enlarged sectional view on the line 4—4 of Fig. 1.

Illustrative of the embodiment disclosed, the brassière is generally denoted B and is characterized by a breast portion 10, the spaced breast sustaining pockets 11, the side portions 12 terminating in the back tapered parts 13 provided with complementary disconnectable fastening means 14 and 15.

Each pocket 11 is of a suitable relatively light weight fabric material and comprises an intermediately arranged one piece hour glass shaped

2

section or intervenor 16 and the laterally or horizontally spaced wings 17. For reinforcing purposes, substantially vertically arranged and spaced parallel lines of stitching 18 are disposed along the entire length of the intervenor or panel 16 which may be said to embody the centrally arranged contracted portion or neck 19 integrally merged with the outwardly flared, expanded, or tapered portions 20 which together with the neck 19 define the concaved margins 21 each characterized as shown by substantially rectilinear sides or edges inclined or sloping outwardly but merged with a respective concaved base portion of the contracted neck portion or part 19.

The side sections or wings 17 of each pocket comprise convex nose portions 22 having the outwardly diverging margins 23. For strengthening purposes horizontal and spaced parallel lines of stitching 24 are provided along the entire width of the wings 17, these lines of stitching are substantially normal to the lines of stitching 18 of the intervenor means or panel 16 prior to securing the wing portions to the intervenor which according to the invention are fastened together by an uninterrupted or continuous or open lattice or fagotting stitch 25. More particularly margins 21 and 23 are first bent inwardly as shown in Fig. 4 and thereafter these margins as well as the body of the intervenor and wings 17 are secured together by the lattice stitching 25 and by the lines of stitching 26. Pursuant to such stitching of the intervenor and wings, a substantially cone shaped pocket is formed having its apex which in fact is at the neck portion free of the inwardly turned margins in part characterizing the inwardly disposed flanges 28, thus leaving the apex zone of the breast sustaining pockets 11 free of impinging flanges to preclude irritation of the nipples of the breasts.

Lines of stitching 27 secure the outer margins of the wings and intervenor of each pocket to the body of the brassière and if desired elastic inserts 29 are secured to the brassière below each pocket and conventional shoulder straps 30 are secured to the upper parts of the intervenors and the tapered side portions 12 of the brassière.

In the assembled and secured relation of the cone shaped pockets as illustrated in Fig. 1 the lines of stitching 18 and 24 form nested angles disconnected by the fagotting stitching 25 with the sides of these angles progressively decreasing in length proportionately to their distance outwardly away from neck portions 19 of the intervenors, thus giving the visual effect of reducing the size of relatively heavy breasts. If desired the reinforcing lines of stitching 18 and

24 of the intervenor and wings of each pocket may be applied prior to assembling and securing these parts together. The concavities formed by the curved margins 21 may be said to be complementary to the horizontally or laterally spaced wings 17 when disposed therein pursuant to securing of the wings to the intervenor.

Briefly recapitulating, the flexible one piece intervenor 16 while substantially hour glass shaped may be said to characterize the horizontally spaced reentrant concavities bounding the narrowest or neck part 19 and the progressively outwardly widening or outwardly flared upper and lower tapered portions as 20.

Various changes may be made in details of construction and arrangement of parts without departing from the spirit of the invention or sacrificing any of the advantages thereof inherent therein.

I claim:

1. A breast sustaining pocket for brassières; comprising, a one piece substantially hour glass shaped intervenor having an intermediately arranged contracted part provided with opposed concaved base portions and having upper and lower tapered portions integral with and flaring away from said contracted part, said tapered portions and said contracted part defining spaced concavities having sides merging with and diverging outwardly away from said base portions, wings disposed within said concavities and having convex nose portions disposed adjacent to said base portions and including outwardly diverging margins arranged contiguous to said sides, and means securing said nose portions to said base portions and said sides to said margins.

2. A breast sustaining pocket for brassières; comprising, a one piece flexible intervenor having an intermediately disposed contracted part provided with spaced concaved base portions and having upper and lower tapered portions integral with and progressively widening outwardly away from said contracted part, said tapered portions and contracted part defining spaced concavities having sides merging with and diverging outwardly away from said base portions, spaced wings disposed within said concavities and having convex nose portions disposed adjacent to said base portions and including outwardly diverging margins arranged contiguously to said sides, means securing said nose portions to said base portions and said sides to said margins, and parallel lines of stitching disposed on said intervenor and wings.

3. A breast sustaining pocket for brassières; comprising, a one piece substantially hour glass shaped intervenor having an intermediately arranged contracted part provided with opposite concaved base portions and having upper and lower tapered portions integral with and flaring outwardly away from said contracted part, said tapered portions and contracted part defining spaced reentrant concavities having their sides merging with said base portions and diverging outwardly away from said contracted part, spaced wings disposed within said concavities and having convex nose portions disposed adjacent to and within said base portions and including outwardly diverging margins arranged contiguous to said sides, means securing said nose portions to said base portions and said sides to said margins, parallel lines of stitching disposed lengthwise of and secured to said intervenor, and parallel lines of stitching arranged widthwise of and secured to said wings, the said parallel lines

of stitching on said wings and intervenor defining nested angles having their sides progressively decreasing in length proportionately away from said contracted part.

5. A breast sustaining pocket for brassières; comprising, a one piece substantially hour glass shaped intervenor having an intermediately disposed contracted neck part provided with horizontally spaced concaved base portions and having upper and lower tapered portions integral with and flaring outwardly away from said contracted neck part, said tapered portions and neck part defining spaced concavities having inclined sides merging with said base portions and diverging outwardly away from said contracted neck part, horizontally spaced wings straddling said intervenor and disposed within said concavities and having convex nose portions disposed adjacent to and within said base portions and including outwardly diverging margins arranged contiguous to said sides, open lattice stitch means securing said nose portions to said concaved base portions and said sides to said margins, parallel lines of stitching disposed along the entire length of and secured to said intervenor, and parallel lines of stitching arranged along the entire width of and secured to said wings, the said parallel lines of stitching on said wings and intervenor defining nested angles having sides progressively decreasing in length proportionately away from said neck part.

35. 6. A breast sustaining pocket for brassières; comprising, a one piece substantially hour glass shaped intervenor having an intermediately disposed contracted neck part provided with opposed concaved base portions and having upper and lower tapered portions integral with and flaring outwardly away from said contracted neck part, said tapered portions and contracted part defining spaced reentrant concavities having rectilinear diverging sides spreading outwardly away from and merging with said base portions, horizontally spaced wings straddling said intervenor and disposed within said concavities and having convex nose portions disposed adjacent to and within said concaved base portions and including outwardly diverging rectilinear margins arranged contiguous to said sides, open lattice stitch means securing said nose portions to said concaved base portions and said sides to said margins, parallel lines of stitching arranged fully lengthwise of and secured to said intervenor, parallel lines of stitching disposed fully widthwise of and secured to said wings, the said parallel lines of stitching on said wings and intervenor defining nested angles interrupted in part by said open lattice stitch means and having sides progressively decreasing in length proportionately away from said neck part.

60. JACK WOLF.
